UNITED STATES PATENT OFFICE.

CLARENCE V. KOZLAY, OF NEW YORK, N. Y., ASSIGNOR TO S. STROOCK & COMPANY, INC., OF NEW YORK, N. Y., A CORPORATION OF NEW YORK.

DESIGN FOR A TEXTILE FABRIC.

Application filed January 6, 1923. Serial No. 4,828. Term of patent 7 years.

To all whom it may concern:

Be it known that I, CLARENCE V. KOZLAY, a citizen of the United States, residing at New York city, in the county and State of New York, have invented a new, original, and ornamental Design for Textile Fabrics, of which the following is a specification, reference being had to the accompanying drawing, forming part thereof.

The drawing is a piece of textile fabric embodying my design.

I claim:

The ornamental design for a textile fabric as shown.

CLARENCE V. KOZLAY.
